Patented Dec. 15, 1970

219,497

HOLDER FOR A SHOESHINE KIT

William Ernest Kendall Waiting, 3 Market Place,
Brackley, Northampton, England

Filed Jan. 27, 1969, Ser. No. 15,526

Term of patent 14 years

Int. Cl. D28—03

U.S. Cl. D86—11

FIG. 1 is a side elevation of a holder for a shoeshine kit showing my new design;

FIG. 2 is a top plan view thereof;

FIG. 3 is an end elevation thereof;

FIG. 4 is an elevation taken from the opposite end of FIG. 3; and

FIG. 5 is a bottom plan view thereof.

I claim:

The ornamental design for a holder for a shoeshine kit, substantially as shown.
